F-BAR KEY FOR SAXOPHONES

Louis E. Berkson, Fresno, Calif.

Application November 1, 1944, Serial No. 561,415

2 Claims. (Cl. 84—385)

1

This invention aims to

This invention aims to provide a novel mechanism whereby the F-sharp pad or the D-natural pad of a saxophone may be closed to afford the tone specified, without closing the "second" B-flat pad, the term "second" being defined hereinafter.

The invention is easy and inexpensive to install, and it demands no consequential change in accepted saxophone key mechanism, or in fingering.

A mechanic who abides by what is claimed may make such changes as his skill may direct without departing from the spirit of the invention.

In the drawings:

Figure 1 is an elevation showing a portion of a saxophone wherein the invention is embodied:

Figure 2 is an elevation on an enlarged scale, the view-point of Figure 1 having been changed, and parts being sectioned away.

Figure 3 is a cross section on the line 3-3 of Figure 1.

Figure 4 is a longitudinal section on the line 4-4 of Figure 3.

In order that the improvement which characterized the present invention may be under-

the present invention may be understood without surmise, it is necessary, upon the one hand, to describe some portions of a known saxophone structure. Upon the other hand, it is unnecessary to set forth all functions which may be possessed by parts shown and described, so far as they relate to operations not germane to the solution of the specific problem with which the present invention is concerned.

The improvement herein disclosed affords a means whereby, in a saxophone, the specific F-sharp tone pad 5 shown in the drawing may be closed, without closing the specific B-flat pad 6 shown in the drawings, it being possible to perform many passages at an accelerated tempo; for example, that shown in Figure 5 and not including B-flat.

Notice will be given when the description departs from that which is old, and deals with that which is new.

The numeral 1 marks the tubular body of a saxophone. The D-natural tone pad is shown at 2, the E-natural pad at 3, the F-natural pad at 4, the F-sharp pad at 5, and the B-flat pad at 6. The F-sharp pad 5 carries a finger 7, extended longitudinally of the body 1, toward the reed end of the instrument and beyond the perimeter of that pad.

Broadly considered, the finger 7 is known in the art. In the device herein disclosed, however, the finger 7 preferably is shifted from its accustomed position in the direction of the arrow "A," to the end that a rigid, arched bridge 8 may extend

conveniently across the F-sharp pad 5, in spaced relation thereto.

The bridge 8 is one of the characteristic features of the invention, in combination with other parts. One end of the bridge 8 is secured to the F-natural key 4. The opposite end of the bridge 8 projects toward the reed end of the saxophone, beyond the perimeter of the F-sharp pad 5.

Resuming the description of known structure, a shaft 9 extends longitudinally of the body 1, and is supported thereon, as indicated at 10. A sleeve 11 is mounted to rock on the shaft 9 and carries a transverse lever 12, to which the B-flat pad 6 is secured. A sleeve 14 is mounted to rock on the shaft 9. The sleeve 14 has an offset 15. A rigid, longitudinal connection 16 joins the offset 15 with the lever 12, outwardly of the shaft 9. A transverse, inwardly projecting arm 17 is secured to the sleeve 14.

20 Viewed in its broadest aspect, the arm 17 is known in the art; but in the art it is of such length that it extends under the finger 7 on the F-sharp pad 5. The result has been that when the F-sharp pad 5 was closed, the B-flat pad 6 25 was closed also. In the present case, the arm 17 terminates in spaced relation to the finger 7, and the F-sharp pad 5 may be closed without closing the B-flat pad 6. Control over the B-flat pad 6 remains, since the arm 17 extends under the bridge 8, the F-natural key 4, and associated parts, constituting means for closing the B-flat pad. 30

From the viewpoint of installation, the changes wrought in the standard key mechanism are simple, and, therefore, advantageous. The arm 17 is shortened so that it does not extend under the finger 1; the bridge 8 is supplied, and, if desired, the finger 1 may be set over a trifle in the direction of the arrow "A" for the better accommodation of the bridge.

45 By means of structure known in the art, the D-natural pad 2 and the F-sharp pad 5 are interconnected, and the advantages alleged with respect to the operation of the F-sharp pad innure likewise to the benefit of the operation of the D-natural pad.

50   Those skilled in the art are aware that a sophone has, near the bell, a tone pad which gives B-flat below the staff in the treble clef and tenor clef notations. That pad, not shown in the drawings, may be referred to as the "first" B-flat pad, and to avoid confusion, the pad 6 may be denominated the "second" B-flat pad. In the present structure it will be noted that the second B-flat is 55 obtained by depressing the first finger (B-nat-

ural key) 6a, using the finger of the left hand. By also using the first finger of the right hand to depress the F-natural key (4 of Fig. 1) when depressing either the second or third fingers (pads 3 and 2) while the first finger of the left hand is already depressed at pad 6a, B-flat is no longer obtained. Instead B-natural is obtained. This is an important feature of the present invention.

What is claimed is:

1. In a saxophone comprising a body and a B-flat tone pad: a D-natural tone pad, an F-natural tone pad, and an F-sharp tone pad, all located between the D-natural pad and the B-flat pad: mechanism for operating the B-flat pad, comprising a transverse arm, a longitudinal finger carried by the F-sharp pad, the arm terminating in spaced relation to the finger, and a bridge secured to the F-natural pad and extending across the F-sharp pad, in spaced relation thereto, the bridge overhanging the arm and cooperating with the arm to close the B-flat pad. 15
2. In a saxophone comprising a body and a

B-flat tone pad: a D-natural tone pad, an F-natural tone pad, and an F-sharp tone pad, all located between the D-natural pad and the B-flat pad: mechanism for operating the B-flat pad, comprising a transverse arm, and a bridge secured to the F-natural pad and extending across the F-sharp pad, in spaced relation thereto, the bridge overhanging the arm and cooperating with the arm to close the B-flat pad, and a B-natural tone pad above and adjacent to the B-flat pad. 5
